UNITED STATES PATENT OFFICE.

JOHN F. COURSON, OF PITCAIRN, PENNSYLVANIA.

DRAW-GEAR FOR RAILWAY-CARS.

SPECIFICATION forming part of Letters Patent No. 732,521, dated June 30, 1903.

Application filed May 6, 1902. Serial No. 106,179. (No model.)

To all whom it may concern:

Be it known that I, JOHN F. COURSON, a citizen of the United States, residing at Pitcairn, Allegheny county, Pennsylvania, have invented certain new and useful Improvements in Draw-Gear for Railway-Cars, of which the following is a specification.

My invention relates to draw-bars for railway-cars and the like, and particularly to means for taking up or absorbing the initial shock or strain consequent upon the coupling of the cars or upon the starting of the car.

It is my object to provide such an arrangement as will enable me to use a cushioning spring of comparatively low resistance, so that the reaction of this spring will not cause damage to any of the parts.

In the accompanying drawings, Figure 1 is a longitudinal vertical sectional view through so much of the draw-bar and supporting-frame as is necessary to a complete understanding of my invention, parts being shown in side elevation. Fig. 2 is a plan of Fig. 1. Fig. 3 is a cross-sectional view on line 3-3 of Fig. 1. Fig. 4 is a cross-sectional view on line 4-4 of Fig. 1. Figs. 5, 6, 7, 8, and 9 are views of the several plates used in my construction. Figs. 10, 11, 12, 13, 14, 15, 16, 17, 18, 19, and 20 are views of detail parts. Fig. 21 is a view of another arrangement of the key.

The draw-bar comprises a bar 2, having a strap *b* bolted thereto and extending rearwardly therefrom, said strap inclosing the bearing-pieces *c* *d*. Within the strap a series of plates are arranged, these plates being superimposed and those marked 2 being supported rigidly against movement in a direction longitudinally of the draw-bar or car, for which purpose they are provided with recesses at 8 in their sides to fit over toothed holding-bars 7, which are riveted at 9 to the sills 10 or other suitable part of the framework of the car. These bars are toothed at 11, and they are engaged by locking-bars 6, which have arms 12 at their upper and lower ends embracing the series of plates being engaged with the upper and lower surfaces of the upper and lower plates 2. These locking-bars 6 are toothed on their lateral edges to engage the teeth of the bars 7, and when so engaged the draw-bar will be supported from the frame of the

car. The toothed parts are held in engagement by a suitable key 13, which is arranged between the edge of the locking-bar 6 and the edge of the recess in the plate 2. By removing this key it will be seen that the locking-bar 6 may be moved aside to be disengaged from the teeth of the supporting-bar 7, and the draw-bar will then be free to be raised or lowered in relation to the car, and when adjusted to the desired position the toothed parts may be engaged again and held by the key. There are two of these supporting means at each side of the draw-bar and they are similar in all respects.

Between the plates 2, of which there are six shown in the drawings, a series of plates 5 are arranged, these extending from the bearing-piece *d* to the bearing-piece *c* and bearing at their front and rear edges upon the said pieces. These plates are free to move with the draw-bar in a direction longitudinally of the car, as they are not connected with the car-frame. It will be noticed that the plates 2, which, however, are held rigidly against this longitudinal movement, are shorter than the plates 5, leaving spaces at 14, Fig. 1, between their front and rear edges and the pieces *c* and *d*. By this construction it will be seen that the draw-bar is free to move longitudinally in respect to the relatively fixed plates 2. The plates 2 have an opening at their central portions, and springs 15 and 16 are located in the central space thus formed. The plates 5, excepting the upper and lower ones, also have central openings to provide the space for the springs. The spring 15 is much stronger than the spring 16 located within it, and it is borne upon by plates 17, arranged at right angles to the series of plates heretofore mentioned. The inner spring has bearing upon its ends plates 18, and these are arranged to be pressed upon by studs 19 projecting from centrally-arranged plates 3. These plates are transversely grooved on their upper and lower faces, providing a series of inclines or cam-surfaces 20, which are engaged by similar grooved or toothed portions of plates 1, bearing upon their outer edges upon the pieces *c* and *d*, respectively, and at their inner edges bearing upon the transverse plates 17. The form of these plates is shown in Figs. 10 to 13, and those at the front end of the nest of plates

are slightly separated from those at the rear by the space indicated at 21 in Fig. 2, between the inner edges or ends of said plates.

- It will be seen that the spring 15 will provide a cushioning effect whether the draw-bar is forced backwardly upon the impact in coupling the cars or if it is pulled forwardly on starting the car. In either case the plates 5, pushing upon the transverse plate 17, will act to compress the spring 15, the other end of the spring being held by the plate 17 at that end bearing upon the rigid plates 2. It is my object to use a spring of comparatively low power or resistance, and for this purpose I combine with the spring-cushion a friction-applying action whereby the shock or strain will be absorbed by increasing the frictional pressure between the movable and fixed plates. For this purpose the toothed plates are provided, and the spring 16 is used for placing upon the inner plate 3 a yielding resistance to its movement longitudinally with the draw-bar. Supposing, for instance, the draw-bar receives the impact in the coupling operation and is moved rearwardly, the plates 1 will move therewith, and as the centrally-toothed or cam plate 3 is held against free longitudinal movement by the spring 16 the plates 1 will be separated by their toothed portions riding up the inclines of the plates 3, and increased frictional contact will be created between the plates 2 and the plates 5, it being understood that all of these plates are capable of slight adjustment vertically, the arrangement of the holding-bar 7 and locking-bar 6 in the recessed edges of the plates 2 permitting this action. By this arrangement I obtain not only the cushioning effect of the spring 15, but a frictional resistance proportionate to the shock or strain sustained by the draw-bar. The spring 16 prevents any damage to the parts, as this will yield slightly while retarding the movement of the central cam-plate 3. The action is the same whether the draw-bar is pulled forwardly or pushed rearwardly. The form of the friction cam-plate 3 is shown in Fig. 12. It has stop projections 22, which bear upon the inner edges of the supporting-bars 7 of the keys and prevent the said cam-plates from moving in an outward direction. The plates 1 also have stops for a similar purpose, Fig. 10.
- In the arrangement shown the frictional pressure would occur at the forward end of the nest of plates when the draw-bar is pushed backward and it would occur at the rear end of the said nest of plates when the draw-bar is pulled forwardly; but I do not wish to limit myself to this single or independent action of the parts.
- In order to adjust the draw-bar at a point forward of the nest of plates, I provide a supporting band or head 23, Figs. 4 and 20, toothed at 24 on its lateral edges. Toothed holding-bars 25 are secured to the frame of the car and with one of these the toothed band engages. At the opposite side of the band, however, connection between its toothed

portion and the toothed supporting-bar 25 is formed by a double key 26. (Shown in Figs. 4 and 19.) By removing this key the supporting-band may be adjusted up or down together with the draw-bar.

I do not wish to limit myself to the form of cam-plates shown, as the cam or spreading action may be secured in other ways than that described.

The spring 16 serves to return the cam-plates to normal position after each action.

It will be noticed that the same spring 15 answers as a buffer for both the forward and rearward movement of the draw-bar. The one spring serves also to resist the movement of both the cam or wedge plates 3 and to return them to normal position.

It will be seen that the relatively fixed plates 2 serve, in effect, as the abutment between which and the movable plates the spring 15 is interposed. I do not wish to limit myself to the construction shown, in which each plate 2 and each plate 5 is formed in one piece, it being only necessary that an opening be provided for the spring intermediate of the length of the plates.

Some of the plates 2 are formed with central openings, as at $x x'$, Figs. 6 and 8, while others are intact throughout. These latter plates form the upper and lower layer of the nest of plates.

Some of the plates 5 have central openings, as at y , Fig. 9, while others are not so provided, as shown in Fig. 7. The latter plates extend immediately above and below the springs.

The width of the openings $x x' y$ differ according to the position of the plate in relation to the spring, those nearer the top and bottom having narrower openings, as shown in Fig. 3.

In Fig. 21 it will be noticed that the key is placed in rear of the rigid bar 7 instead of in front of the movable locking-bar 6. In order to adjust the draw-bar in this latter case, the key 13 is removed and then the entire draw-bar is pulled forwardly until the teeth of the bar 6 become disengaged from the teeth of the bar 7. The draw-bar is then raised or lowered as desired and is then pushed back, and when the toothed parts of the bars 6 and 7 are again in engagement the key is inserted back of the rigid bar 7.

I claim—

1. In combination, a draw-bar, a plate carried thereby and movable therewith, a relatively fixed plate in contact with the movable plate, resilient means for resisting the movement of the movable plate, and means for increasing the frictional contact between the movable and relatively fixed plates, the said fixed plate serving as the abutment between which and the movable plate the resilient means is interposed, substantially as described.

2. In combination, a draw-bar, a plate extending transversely of the draw-bar and

- fixed in relation thereto, a movable plate carried by the draw-bar, a single buffer-spring adapted to act against the movement of said plate when the draw-bar is moved in either direction and means for increasing the frictional contact between the plates when the draw-bar is pushed or pulled, substantially as described.
3. In combination, a draw-bar, a plate connected with the frame and fixed in relation to the draw-bar, a plate movable with the draw-bar, said plates having openings at their central portions, a spring located in the space thus formed and arranged to be compressed by the edges of the fixed and movable plates when the draw-bar is either pushed or pulled and means for varying the frictional resistance between the fixed and movable plates, substantially as described.
4. In combination, the draw-bar, a plate carried thereby and movable therewith, a relatively fixed plate in contact with the movable plate, a buffer-spring arranged intermediate of the front and rear ends of the plates and arranged to be compressed between the edges of the fixed and movable plates when the draw-bar is moved in either direction and means for varying the frictional pressure between the fixed and movable plates, substantially as described.
5. In combination, a draw-bar, a plate carried thereby and movable therewith, a relatively fixed plate in contact with the movable plate, a spring arranged intermediate of the front and rear of the plates, wedge or cam plates 3, one for each end of the nest of plates, a spring interposed between the plates 3 and plates 1 to be acted on by the cam-plates, substantially as described.
6. In combination, a draw-bar, a plate carried thereby, a plate relatively fixed and in contact with the movable plate, a buffer-spring arranged intermediate of the front and rear end of the plates, a wedge or clamping member at each end of the plates and a spring interposed between said clamping members, substantially as described.
7. In combination, a draw-bar, a plate carried thereby, a relatively fixed plate connected with the car, a spring 15 arranged intermediate of the front and rear end of the superimposed plates, and arranged to act upon movement of the draw-bar in either direction, plates 17 interposed between the ends of the spring and the edges of the plates, clamping means and a spring 16 inclosed within the spring 15 and interposed between the clamping means, substantially as described.
8. In combination, a draw-bar, a friction member movable therewith, a relatively fixed friction member in contact with the movable member, resilient means for resisting the movement of the movable member and means for increasing the frictional contact between the movable and relatively fixed members, the said fixed member serving both as the

friction member and also as the abutment between which and the movable member the resilient means is interposed, substantially as described.

9. In combination with the draft-bar, two friction members consisting of two flat plates, one movable and the other relatively fixed, a yielding resistance medium and an abutment for holding the relatively fixed member 75 against movement in either direction by engaging shoulders thereon, said shoulder projecting laterally from the edge of the plate, substantially as described.

10. In combination with a draft-bar, two 80 friction members, one movable and the other relatively fixed, a yielding resistance and abutment means for engaging laterally-arranged shoulders on the friction members to hold the fixed member against movement in 85 either direction, substantially as described.

11. In combination with a draft-bar, a friction member recessed on its edge and means in said recess connected with the car-frame for holding the said member removably in 90 place and a coacting friction member, substantially as described.

12. In combination with a draft-bar, a strap, friction-plates carried by the said strap, wedge means for increasing the frictional pressure 95 between the plates, a spring interposed between the edges of the friction-plates and an abutment for holding the strap to the car and for holding one of the friction-plates in fixed relation to the other, substantially as described. 100

13. In combination, a draft-bar, a nest of plates, a strap carrying said nest of plates, said plates being laterally recessed to provide shoulders, and abutments connected with the car-frame to hold the said plates in position, substantially as described.

14. In combination, a draft-bar, friction members and vertically-arranged abutment means connected with the car, said abutment 110 means engaging one or more of the friction members, said friction member being detachable from the abutment means by moving the same vertically, substantially as described.

15. In combination, friction members, carrier means therefor, means for holding the carrier to the car-frame comprising a shifting locking member and means for holding one of the friction members against movement in either direction, substantially as described. 115 120

16. In a draw-gear and buffing apparatus, the combination with a friction element capable of forward and backward movement from its normal position and having friction-faces parallel to the line of draft, of secondary friction elements in fixed positions and having friction-faces contacting with the friction-faces on the primary friction element, and a wedging device for creating friction between the primary and secondary friction elements, 125 substantially as described. 130

17. In a draw-gear and buffing apparatus,

the combination with a movable friction element, and a fixed friction element, an interposed spring having a bearing at both ends against the fixed friction element and resisting the movement of the movable friction element in either direction, substantially as specified.

In testimony whereof I affix my signature in presence of two witnesses.

JOHN F. COURSON.
